UNITED STATES PATENT OFFICE.

HENRY P. KRAFT, OF RIDGEWOOD, NEW JERSEY.

EXTRACTING-TOOL.

1,389,667.

Specification of Letters Patent.

Patented Sept. 6, 1921.

Application filed March 1, 1916. Serial No. 81,342.

To all whom it may concern:

Be it known that I, HENRY P. KRAFT, a citizen of the United States of America, residing in Ridgewood, in the county of Bergen and State of New Jersey, have invented 5 certain new and useful Improvements in Extracting-Tools, of which the following is a specification.

This invention relates to extracting tools, 10 and aims to provide certain improvements therein.

The invention is particularly directed to a tool for extracting the inside working parts from pneumatic valve casings, although it 15 is adapted for other analogous purposes. In the standard pneumatic tire valve the working parts usually comprise a seat member which is held within the casing by a screw-threaded plug to which the seat 20 member is swiveled. Below the seat member is a valve proper and beneath the valve proper is a loading spring, the various parts being held together by a pin which extends through the entire length of the valve in 25 sides. It sometimes happens that the parts are screwed into the casing so tightly that the seat member becomes jammed in place with such force that when its screw-threaded plug is unscrewed, the flange on the plug 30 which forms a part of the swiveled connection gives away, leaving the seat member in place. The present invention provides a tool which is adapted to be inserted in the valve shell for grasping the seat member and 35 exerting sufficient tension thereon to remove it.

In the accompanying drawings, wherein several modifications of the invention are 40 illustrated,—

Figure 1 is a sectional view of one form 45 of tool as applied to a valve, showing part of the tool in elevation.

Fig. 2 is a similar view, the tool being shown in section and in the act of withdrawing the valve insides.

Fig. 3 is a section on the line 3—3 in Fig. 2.

Fig. 4 is an underside view of the tool.

Fig. 5 is an elevation of a part of the tool.

Fig. 6 is a sectional view of another form 50 of tool.

Fig. 7 is a sectional view of still another form.

Fig. 8 is a cross section on the line 8—8, 55 Fig. 7.

Referring first to Figs. 1 to 5, let A indicate a valve casing of standard construction which is formed with a bore to receive the working parts or insides B. Such working parts or insides usually comprise a seat 60 member C carrying a packing D which is pressed against a tapered shoulder E on the inside of the valve casing. The valve proper F is arranged below the seat member and is normally pressed upward by a spring G reacting 65 against a spring holder H. Above the seat member C is commonly employed a screw-threaded plug (which is not shown), the function of which is to press the seat member downwardly against the shoulder 70 E. This plug is usually swiveled to the seat member, a part of the swivel connection comprising a flange I formed on the seat member. The parts are usually held together by a pin J which extends through all of the 75 parts. When for any reason the seat member is forced downwardly so tightly that it binds against the shell to the extent that unscrewing the plug cannot remove it, it is found that the corresponding flange on the 80 screw-threaded plug is nearly always the part which gives away in the act of unscrewing it. This leaves the seat member in place with all or part of the flange I intact.

The tool provided by the present invention is indicated as a whole by the reference letter K. It comprises two or more hook sections L L' which are best formed integrally with a body portion M, the hook sections normally springing apart 85 sufficiently to bring them into the position shown in Fig. 1. In this position they are adapted to slip down through the top of the valve casing, their hooks L' being sufficiently separated to pass over the flange I. Each 90 of the hook sections has a bevel or cam face O, which cam faces are adapted to be engaged by a sliding sleeve P to press the sections together to engage the flange I, as shown in Fig. 2. The body portion M is 95 preferably screw-threaded as shown at Q and working on the screw-thread is a nut R, the function of which is to pull the hook sections upwardly after they are engaged with the flange I.

It is very desirable in the operation of the tool that after the hook sections are engaged they shall be drawn upwardly in a direction which is along the axis of the valve casing. If they are permitted to tilt 100

to one side or the other the valve parts may be bent so as to render them very difficult to remove, or so much strain may be placed upon the flange I that it will break off. For the purpose of keeping the parts in the center, the sleeve P is formed with a bearing face P' which is adapted to contact with the upper edge A' of the valve casing, so that as the sleeve P is forced 10 down after the hook sections are inserted, the bearing faces meet and the tool is held in axial alinement with the valve casing. The nut R is then screwed down idly until it reaches the upper end P² of the sleeve 15 P whereupon it reacts against the sleeve and a further movement of the nut pulls the hook sections outwardly in direct line until the valve parts are sufficiently loosened to enable them to be withdrawn by 20 merely pulling the entire tool away from the valve. To assist in the operation of the sleeve handles P³ may be provided. It is preferable that the sleeve should not have a rotative movement with regard to the 25 hook sections, and for this purpose the faces P⁴ of the sleeve may be flattened and the corresponding faces Q⁴ of the screw-thread Q may also be flattened.

The construction shown in Fig. 6 does not 30 differ essentially from that just described. In this construction the hook sections L³ are formed with cam faces O² O³ and the sleeve P⁶ is more elongated than in the former figures. A similar nut R² is provided 35 for pulling up the hook sections after the sleeve is in contact with the top of the valve.

In Figs. 7 and 8 is shown a slightly different construction. In this form the hook 40 sections L⁴ L⁵ are formed with a screw-threaded shank or body portion Q⁵, upon which screws a nut R². But in this construction the sleeve P⁷ is swiveled to the nut R³ by means of the groove S and pin 45 T. Thus the sleeve has no preliminary sliding movement independently of the nut, but on the contrary moves downwardly as the nut is turned. The tool being in the 50 position illustrated in Fig. 7, the nut is rotated until the bearing face P⁸ strikes the top of the valve, thus causing the sleeve to act upon the cam faces O⁴ O⁵ until the hook sections grasp flange I and a continuance of this movement pulls out the insides. 55 The tool is provided with a handle U which may be grasped by the user during the op-

eration, so as to prevent rotation of the tool as the nut is screwed downward.

While I have shown and described several forms of the invention it will be understood I do not wish to be limited thereto, since various changes may be made therein without departing from the invention. It will also be understood that the tool provided by the invention is applicable to other 60 purposes than those described.

What I claim is:—

1. In an extracting tool, the combination of a normally expanded resilient member adapted to engage the part to be extracted, 70 means for moving such member into such engagement, and means for moving the member to withdraw such part, said last-named means reacting against said first-named means.

2. In an extracting tool, the combination of a plurality of normally expanded resilient hook sections, means for moving the hook sections into engagement with the part to be extracted, and means for withdrawing the hook sections, said last-named means reacting against said first-named means.

3. In an extracting tool, the combination of a plurality of hook members, means for moving said normally expanded resilient 85 hook members into engagement with the part to be extracted, said means being adapted to bear against the object containing the part to be extracted so as to center the device, and means reacting against said first-named means to withdraw the hook sections.

4. In an extracting tool, the combination of a plurality of hook sections, a sleeve for moving said normally expanded resilient hook sections into engagement with the part 95 to be extracted and a nut reacting against said sleeve to withdraw the hook sections.

5. In an extracting tool, the combination of a plurality of hook sections, a screw-threaded member formed integrally with 100 said hook sections, said hook sections being normally sufficiently separated to pass over the part to be extracted, a sleeve surrounding said hook sections and adapted to be moved toward the part to be extracted 105 to move the hook sections into engagement therewith, and a nut screwing on said screw-threaded member and reacting against said sleeve to withdraw the hook sections.

In witness whereof, I have hereunto 110 signed my name.

HENRY P. KRAFT.
